Primary Examiner — Marie D. Fast Horse

(74) *Attorney, Agent, or Firm* — CHRISTENSEN
O'CONNOR JOHNSON KINDNESS PLLC

(57) **CLAIM**

The ornamental design for a graphics tablet, as shown and described.

DESCRIPTION

FIG. 1 is a front-right-top perspective view of a graphics tablet according to an embodiment of my new design;

FIG. 2 is a rear-left-bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged partial front-right-top perspective view thereof as indicated in FIG. 1;

FIG. 10 is an enlarged partial top plan view thereof as indicated in FIG. 7;

FIG. 11 is a front-right-top perspective view of a graphics tablet according to another embodiment of my new design;

FIG. 12 is a rear-left-bottom perspective view thereof;

FIG. 13 is a front elevational view thereof;

FIG. 14 is a rear elevational view thereof;

FIG. 15 is a left-side elevational view thereof;

FIG. 16 is a right-side elevational view thereof;

FIG. 17 is a top plan view thereof;

FIG. 18 is a bottom plan view thereof;

FIG. 19 is an enlarged partial front-right-top perspective view thereof as indicated in FIG. 11; and,

FIG. 20 is an enlarged partial top plan view thereof as indicated in FIG. 17.

The dash-dot-dot broken lines in the drawings show the reference to and extent of the enlarged views only and form no part of the claim. All other broken lines in the drawings depict portions of the coordinate input device that form no part of the claimed design.
